UNITED STATES PATENT OFFICE

2,579,881

AMALGAMATING MACHINE

Wesley Styles, Minneapolis, Minn.

Application March 18, 1946, Serial No. 655,282

1 Claim. (Cl. 209—205)

1

My present invention relates to an improved machine for separating precious metals, such as gold and the like, from placer or other rather finely divided ores and, generally stated, consists of novel devices, combinations of devices and arrangement of parts hereinafter described and defined in the claim.

As is well known, gold is the precious metal most usually separated from its bearing ore by the process known as amalgamation, and mercury is the amalgamator generally employed for this purpose.

An important object of the present invention is the provision of a machine of the general character described by means of which a greater percentage of the gold or other precious metal in placer or similar ore may be separated from the ore than has been possible with prior art machines.

A further object of the invention is the provision of an improved machine of the kind and for the purpose set forth wherein finely divided ore in sludge form will be prepared for and subject to the process of amalgamation while passing through a single chamber of the machine. In this connection attention is called to the fact that the gold bearing particles of placer ores in particular are often coated with a substance not soluble in the mercury or other suitable amalgamator and, that if such coating be not removed, the gold bearing particles so coated will be carried over and discharged with the residue sludge. In accordance with the present invention I largely overcome this loss of precious metal by passing the gold bearing ore in wet or sludge form through an amalgamating chamber containing a suitable quantity of amalgamating medium, such as mercury, and providing in said chamber means whereby the ore is continuously subject to the following compound action, to wit: (a) a violent agitation of the ore which subjects the particles to a scrubbing action tending to polish off the protective coating or layer; (b) a violent impingement of the ore particles against a hard and preferably roughened surface tending to actually crack as well as wear or polish off the protective coating; and (c) producing a violent and thorough mixing of the ore particles with the amalgamating mercury or medium. In the preferred embodiment of the invention illustrated, this multiple action is accomplished in a non-rotary or stationary amalgamating chamber of generally cylindrical shape having a roughened peripheral surface to aid in cracking and scouring the coating mentioned and con-

2

taining a rotary agitator to produce the above mentioned violent agitation of the ore sludge for the purpose of scrubbing and mixing with the amalgamating medium and which also throws the sludge against the stationary peripheral wall of the chamber with great force which tends to crack the coatings on the particles in the manner mentioned.

In machines of the type herein illustrated, in which the amalgamating chamber is horizontally elongated and formed in a stationary housing, some difficulty has been encountered in maintaining a uniform level of mercury or other amalgamating medium throughout the length of the amalgamating chamber throughout the amalgamating process and the tendency of the continuously moving body of ore sludge to draw the mercury amalgamator toward the output end of the amalgamated chamber. In fact, in some cases, this dragging action of the moving column of sludge on the mercury tends to build up the mercury level at the output end of the amalgamating chamber above the residue sludge outlet and, of course, if this happens, there is an immediate loss of valuable mercury or equivalent amalgamator.

Another object, therefore, of the present invention is the provision of an improved structure wherein the level of mercury, or other amalgamator, will remain substantially constant from one end of the amalgamating chamber to the other end thereof regardless of the velocity of sludge movement longitudinally of the amalgamating chamber, and to this end I provide, in accordance with the present invention, a return passage for the mercury, or other amalgamating medium, leading from the lower output end portion of the amalgamating chamber to the lower input end portion of the amalgamating chamber. Preferably, but not essential, this return passage is equipped with a suitable power driven pumping mechanism for producing a continuous circulation of the amalgamator from the output end back to the input end of the amalgamating chamber. In accordance with the preferred embodiment of the invention herein illustrated, the said return passage is in the form of an elongated cylinder and is equipped with an impeller in the nature of a feed screw-like auger.

The above and other highly important objects and advantages of the invention will be made apparent from the following specification, claim and appended drawings.

In the accompanying drawings like characters indicate like parts throughout the several views.

Referring to the drawings:

Fig. 1 is a vertical axial sectional view through the machine incorporating a preferred embodiment of the invention;

Fig. 2 is a view in left end elevation of the machine shown in Fig. 1; and

Fig. 3 is a transverse vertical sectional view taken on the line 3—3 of Fig. 1.

In the drawings the housing of the amalgamating machine is indicated as an entirety by 1 and comprises a horizontally disposed drum-like section 2 and removable heads 3 and 4 respectively. The intermediate drum-like section 1 of the housing is formed with an elongated horizontally disposed cylindrical bore providing an amalgamating chamber, and below said bore 5 the drum-like section 2 is formed with a cylindrical bore 6 that opens into the lower output end portion of the amalgamating chamber through a port 7 and opens into the lower input end portion of the amalgamating chamber through a port 8. The bore 6 extends in parallel spaced relation to the amalgamating chamber forming bore 5 and provides, together with the ports 7 and 8, a return passage for the amalgamator from the output back to the input end portion of the amalgamating chamber. As previously indicated, the bore 6 is preferably provided with a suitable pumping device or impeller and does, therefore, serve also as a pumping chamber. In the preferred embodiment of the invention illustrated, the pumping device or impeller is in the nature of a screw-type conveyor or auger 9 journaled at its opposite ends in the opposite heads 3 and 4 respectively. The heads 3 and 4 are anchored to the opposite ends of the housing section 2 by screws, or the like, 10. The rotary agitator of the amalgamating chamber is indicated as an entirety by 11 and comprises an axially spaced series of disc-like agitator blades 12 press fit on a power driven rotary shaft 13 with suitable spacing washers 14 applied between the blades 12. The agitator thus formed is an elongated affair extending substantially coaxially of the amalgamating chamber with opposite end portions of its shaft 13 journaled in the heads 3 and 4 respectively. One end of the shaft of the impeller 9 and a corresponding end of the agitator shaft 13 extend through the housing head 3 and are connected by intermeshing gears 15. The shaft 13 may be driven from any suitable source of power, such as an electric motor, or the like, not shown. The housing head 3 is provided with an axial or sludge inlet passage 16, and the head 4 is provided with a similar residue sludge outlet passage 17.

An inlet pipe 18 leads downwardly into the passage 16 and an outlet pipe or conduit 19 leads downwardly from the residue outlet passage 17. The machine shown is supported by legs 20 formed integrally with the heads 3 and 4 respectively, and a suitable petcock 21 is provided for draining the mercury or other liquid amalgamating liquid from the amalgamating chamber and from the underlying bore 6 through the bottom wall of the housing.

Preparatory to operation, the mercury, or other suitable amalgamating fluid, will be injected into the amalgamating chamber through the inlet 18 in quantity sufficient to fill the impeller-equipped pump chamber 6 and to bring the level thereof in the amalgamating chamber 6 up to a point above the bottoms of the agitator blades 12 but below the bottom of the outlet passage 17. Also the agitator shaft 13 will be

driven at high speed which will, through the reduction gears 15, drive the auger-like impeller 9 at a reduced speed with respect to the speed of the shaft 13 and its agitator 11. To separate gold, or the like, from placer or similar finely divided ore, the ore will be injected into the amalgamating chamber 5 through the inlet pipe 18 and cooperating passage 16 in wet or sludge form, and will flow through the amalgamating chamber to and out of the outlet passage 17 and discharge pipe 19. The flow through the machine can be continuous and will keep the ore sludge level in the amalgamating chamber above the bottom of the outlet passage 17. The rate of delivery of sludge ore to the inlet end of the amalgamating chamber should, however, be controlled to keep the sludge level in the amalgamating chamber below the axis of said chamber and the rotary agitator level.

As the sludge ore passes through the amalgamating chamber, it will be subject to violent agitation by the rotor blades 12 which will produce the aforementioned compound action which to repeat is as follows: (a) the violent action of the ore sludge will cause the particles thereof to be scrubbed against one another and against the roughened wall of the amalgamating chamber and surfaces of the agitator blades which will tend to scrub off or polish off the amalgamation inhibiting coatings on the gold bearing particles; (b) the sludge ore will be thrown radially outwardly by the rotating agitator blades 12 against the roughened surface of the amalgamating chamber with great force which will tend to crack the said amalgamation inhibiting coatings on the ore particles; and (c) the ore sludge will be thoroughly intermixed with the mercury, or other amalgamating medium, which is heavier than the ore sludge and will tend to remain at the bottom of the amalgamating chamber. Of course, all during this operation the mercury amalgamator will be continuously circulated over the bottom of the amalgamating chamber from the input toward the output end thereof and then returned to the input end of the amalgamating chamber by the auger 9 through the port 7, passage 6 and port 8. As previously indicated, this continuous returning of the mercury from the output end portion of the amalgamating chamber back to the input end portion thereof will automatically maintain the mercury level in the amalgamating chamber substantially uniform throughout the length of the chamber and will thereby eliminate the possibility of the mercury being carried over into the outlet passage 17 as a result of the flow of ore sludge in that direction. By reference to Fig. 1 it will be seen that the above mentioned roughened surface of the amalgamating chamber 5 may be produced by providing therein a closely spaced series of circular grooves or corrugations.

In practice it has been found that a larger percentage of the gold bearing particles in the ore will be removed during its passage through my improved machine than has been hitherto possible with prior art machines which, for the large part, are much more complex. In fact, it has been found that only a very small percentage of gold bearing ore will be carried over into the outlet passage 17 with the residue sludge, and that an unusually large percentage of the gold bearing ore will be successfully amalgamated, this being due no doubt to the fact that the ore is successfully cleaned and otherwise prepared for amalgamation in the manner described. Peri-

odically, of course, the amalgamating mercury, or the like, will be drained off through the petcock 21 and replaced.

What I claim is:

In an amalgamating machine, a stationary housing providing a horizontally elongated generally cylindrical amalgamating chamber adapted to contain a body of fluid amalgamating medium to a predetermined static level, an ore sludge inlet passage through one end wall portion of the amalgamating medium, a residue sludge outlet through the other end wall portion of the amalgamating chamber and located above the static level of the amalgamating medium, the inner wall surface of the stationary housing defining the periphery of the amalgamating chamber being roughened to aid in scouring and cracking of the amalgamation inhibiting coating on the ore particles, a horizontally elongated rotary agitator within the amalgamating chamber and journaled in the end wall portions of said housing, said rotary agitator comprising a series of axially spaced agitating blades, power means for driving said agitator at high speed, whereby to produce a severe impingement of the ore particles against the roughened interior surface of the housing wall, said housing being formed below the amalgamating chamber thereof to provide an elongated cylindrical pump chamber extending substantially parallel to the amalgamating chamber, said housing wall being provided with an amalgamating fluid outlet passage from the lower portion of the amalgamating chamber at the output end thereof to one end of said elongated pump chamber, said housing wall being provided with a

second passage at the opposite end of the pump chamber providing an amalgamating liquid return from the pump chamber to the bottom portion of the amalgamating chamber at the input end thereof and below the sludge inlet passage therethrough, and a power driven screw within said elongated pump chamber for maintaining a positive circulation of amalgamating fluid from the output end of the amalgamating chamber to the input end thereof within the pump chamber and thence from the input end to the output end thereof within the amalgamating chamber.
